[57] **CLAIM**

The ornamental design for a deceleration warning light,
as shown and described.

DESCRIPTION

FIG. 1 is a front elevational view of the deceleration
warning light showing my new design;
FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof; and,
FIG. 7 is a front perspective view thereof on a reduced
scale, the fragmentary car being shown in broken lines
for illustrative purposes only.

FIG. 1

FIG. 2

FIG. 3

FIG. 4

FIG. 5

FIG. 6

FIG. 7
